J. M. LARSH

ROAD VEHICLE STEERING MECHANISM

Filed March 17, 1926

Patented May 17, 1927.

1,628,851

UNITED STATES PATENT OFFICE.

JOHN M. LARSH, OF INDIANAPOLIS, INDIANA, ASSIGNOR, BY DIRECT AND MESNE ASSIGNMENTS, OF ONE-FOURTH TO WILLIAM MODE TAYLOR AND ONE-FOURTH TO ULYSSES GRANT SMITH, BOTH OF INDIANAPOLIS, INDIANA.

ROAD-VEHICLE STEERING MECHANISM.

Application filed March 17, 1926. Serial No. 95,227.

This invention relates to steering mechanism for road vehicles which is particularly adapted for use with road making machines although capable of use on wheeled vehicles of any kind, and is a continuation in part of my application for patent on a road making machine filed January 4, 1926, Serial No. 79,245.

One object of my invention is to change the planes of the front wheels relative to the longitudinal axis of the machine without changing the direction of a tongue supporting the steering mechanism.

Another object is to provide means, manipulated from a rear platform, for controlling the direction of travel of the machine without conflicting with an entirely separate means of steering by side motion of the tongue; and a further object is to provide an auxiliary pulling tongue, adapted for angular variation from the direction of travel of the machine with or independently of a tongue supporting a steering mechanism, to allow draft animals to secure footing on firmer ground to one side when the ground directly ahead is soft or less suitable.

I accomplish the objects of this invention by the means illustrated in the accompanying drawing in which: Fig. 1, is a side elevation of a road making machine embodying my improvements. Fig. 2 is a detail in side elevation of the front axle with the wheel removed, and of an adjacent portion of the steering tongue and associated steering mechanism, Fig. 3 is a portion of Fig. 2 on a larger scale and Fig. 4 is a top plan view of the mechanism shown in Fig. 2; the scale of the last three figures being larger than that of Fig. 1.

Like characters of reference indicate like parts in the several views of the drawing.

Referring to the drawing, 1 is the body frame of the machine, 2 the front and 3 the rear road wheels. A block 70 is connected by vertical angle-bar standards 72 with the body frame 1, and also by diagonal braces 202. The wheels 2 are mounted on axle-stubs on vertical spindles 52 which spindles are pivotally supported by an axle 35 which is held from skewable adjustment, which requires the wheels 2 to be turned with spindles 52, to steer or change the direction of travel of the machine. The axle 35 is movable endwise of itself by the action of a pinion 37 on a rack 36 carried by the axle.

Attached to the block 70, is a drawbar 71, which terminates at each end with an eye, as clearly shown in Figs. 1 and 2. Connected with the eye at the front end of the draw bar, by a link 73, is a steering tongue 74, the front end of which is free to swing about the link as a hinge; and pivoted under the rear end of the steering tongue 74 is a draft tongue 75, the front end of which is hitched to a tractor, horse teams, or other draft power (not shown). The weight of the tongue 74 is resiliently supported from the body frame 1 by a spring-link 53. The tongues 74 and 75 at their forward portions are normally united by lashings, a slip-ring or other well known means, not shown, so the tongue 74 will not swing or vibrate independently by movement of the wheels over uneven road surfaces.

Slidably mounted in a suitable horizontal opening in the tongue 74, is a box 81, through which slides a pair of channel bars 77, 77, turned with their channels toward each other, and with their adjacent flanges separated, such as to form side slots for the passage therethrough of a shaft 80, on which, within the channels, is a spur gear wheel 79. A rack bar 78 is secured in the channel of the upper bar 77, and the spur gear wheel 79 is in engagement with this rack bar.

The shaft 80 is suitably journaled in a box 81, supported in the horizontal opening in the tongue 74. Mounted on the shaft is a worm wheel 82, which is driven by a worm 83, on the lower end of a vertical shaft 84. The box 81 has a vertical pin 54, which passes between the tongue and a guide bar 55, attached to the tongue, and extending parallel therewith, when it is desired that the machine move in a straight course, but upon turning or varying from a straight course the pin is withdrawn, thereby leaving the bars 77 free to be moved lengthwise of themselves.

The shaft 84, as shown in Fig. 1, is in two telescoping members, and has a universal joint 85. The shaft terminates at its upper end with a bevel wheel 86 which is driven by a bevel pinion 87, on a shaft 88, that extends back to a crank 89, located above a platform 34 upon which an operator stands.

The shaft 88 has universal joints 90, 90. By the operation of the above described

mechanism, when the crank 89 is turned, the rack bar 78, and of necessity the channel bars 77 attached to it, are moved lengthwise through the tongue, and it is obvious, that, 5 by suitably connecting the ends of the bars 77 with the axle stubs on which the front wheels 2 are mounted, the wheels will be turned in a direction to steer the machine. To this end the spindles 52, which are integral with the axle-stubs, are formed with forwardly projecting arms 91, 91, and these are connected by link bars 100, 100, with the respective ends of the bars 77. The link bars here shown have vertical joints 56, 56. 10 The bars 77 and box 81 slide lengthwise of the tongue, to the adjusted positions required by the swing of the front wheels 2 to the position of the bars, as indicated by the dotted lines in Fig. 4.

20 To prevent injury to the machine by contact of a front wheel, or its hub, with a pole or other road obstruction, I provide a release in the form of a breakable pin 25, of wood, or the like, which will break and 25 allow the contacting member to give way when the strain exceeds the resistance of the pin, and the breakage is repaired by inserting a new pin.

Connected with the eye at the rear end of 30 the drawbar 71, is an eye-bolt 102, by means of which a drawbar 101, is connected, and a pull on the tongue is directly transmitted through the draw-bar 71. The scraper blade 4 is connected with the drawbar 101, and 35 thus the draft power is transmitted with the greatest advantage to the accomplishment of the useful work of the machine.

Attention is called to an important feature 40 of my invention afforded by the adaptation of a tongue 74 swingingly attached to the short draw-bar 71, with means attached to said tongue for steering by the usual side motion of the tongue, but having, at the same time, an entirely independent means 45 for steering, operated from another part of the machine. These two means for steering may either be operated separately to steer the machine, or they may both be used simultaneously without any mechanical interference. Frequently a road making machine 50 becomes mired in soft ground or is so situated that an adequate straight-ahead pull is unavailable; but by swinging the tongue unit to one side as shown by dotted lines 55 in Fig. 4, draft animals will be able to get a foot hold on firmer ground, or a tractor operated to better advantage. The steering as controlled independently of the pulling tongue, is by the means hereabove described.

60 I claim:

1. The combination, with a road making machine having a body portion, of a front axle supporting the front end of the machine body; wheels supporting the axle at 65 its ends; a tongue swingingly connected with

the front axle; and means for changing the planes of the front wheels relative to the axle for steering the machine without changing the position of the tongue relative to the axle nor the position of the axle relative to 70 the machine body.

2. The combination, with a road making machine having a body portion, of a front axle supporting the front end of the machine body; wheels supporting the axle at 75 its ends; a tongue swingingly connected with the front axle; and means supported by the tongue for changing the planes of the front wheels relative to the axle for steering the machine without changing the position of the tongue relative to the axle nor the position of the axle relative to the machine body.

3. The combination, with a road making machine, of a tongue swingingly connected with the machine; a bar movable lengthwise of itself and laterally of the tongue across the tongue; a front axle; spindles pivoted vertically to the axle ends and having rigid forward arms; road wheels on the spindles; link-bars connecting the ends of the movable bar with the respective spindle-arms; and means for moving the bar to rock the spindles and change the angles of the wheels to steer the machine without changing the position of the tongue relative to the axle nor the position of the axle relative to the machine body.

4. The combination, with a road making machine, of a steering tongue swingingly connected with the machine; a box sliding longitudinally of the tongue; a pinion journaled in the box; means for manually rotating the pinion; a rack-bar moved lengthwise of itself and laterally of the tongue by the pinion; a front axle; spindles pivoted vertically to the axle ends and having rigid forward arms; road wheels on the spindles; and link-bars connecting the ends of the rack-bar with the respective spindle-arms.

5. The combination, with a road making machine having a body portion, of a front axle supporting the front end of the machine body, said axle as a unit being movable lengthwise of itself but not skewable; wheels supporting the axle at its ends; and means moving with the wheels for changing the planes of the wheels relative to the axle for steering the machine without changing the point of attachment of the tongue relative to the machine body.

6. The combination, with a road making machine having a body portion and a tongue, of a front axle supporting the front end of the machine body, said axle as a unit being movable lengthwise of itself but not skewable; wheels supporting the axle at its ends; means moving with the wheels for changing the planes of the wheels relative to the axle for steering the machine, and means man-

ually operated at the rear end of the machine body for steering the machine with the front wheels independently of any steering action of the tongue.

5 7. The combination, with a road making machine having a body portion, of a front axle rigidly attached to the body and a tongue a pair of road wheels supporting the front end of the body, and a pair of road 10 wheels supporting the rear end of the body; means comprising vertical rockable spindles connecting the front wheels with the front axle for changing the planes of the front pair of wheels to steer the machine, means 15 manually operated at the rear end of the machine body for rocking the vertical spindles at the front end of the machine body to steer the machine and a separate means operated by the tongue for rocking the spindles to steer the machine.

20 8. A road making machine comprising a front axle, spindles pivoted to the ends of said axle having forwardly extended rigid arms, road wheels mounted on the spindles, 25 a connecting bar pivoted at its outer end to the steering means and attached at its other end to a spindle arm and attaching means comprising a pair of pins one of which is adapted to break at a predetermined strain 30 to allow the adjacent road wheel to swing on its spindle.

35 9. The combination, with a road making machine, of a tongue flexibly attached to the front axle, means carried by the tongue for steering the front wheels of the machine by the side movement of the tongue, a separate steering means operated from a different part of the machine, said two means being 40 jointly or separately operable and each selectively operable to augment or retard the steering movement of the other.

45 10. The combination, with a road making machine having a machine body, of an axle supporting the front end of the body said axle having an adjustment lengthwise of itself relative to the body but not skewable; a pair of wheels supporting the axle; a tongue swingingly connected with the axle; means connected with the tongue for changing 50 the planes of the wheels relative to the axle to steer the machine; said means being operable by the side swing of the tongue, and a second means operated from another part of the machine, both means being operable 55 jointly or separately.

60 11. The combination, with a road making machine, mounted on wheels, of means for changing the directions of the planes of the wheels to steer the machine, a tongue a second steering means operated from a different part of the machine, said means for changing the planes of the wheels being operable without interference with the swinging of the tongue or with the second steering 65 means.

12. The combination, with a road making machine, mounted on wheels, of means for changing the directions of the planes of the wheels to steer the machine, a tongue swingingly connected to the front axle and a second steering means operated from a different part of the machine, said means for changing the planes of the wheels being operable without interference with the swinging of the tongue or with the second steering means. 70 75

13. The combination, with a road making machine, of a tongue swingingly connected at its rear end to the machine, a pair of front wheels, means contacting the tongue to change the planes of the front wheels to steer the machine, and a suspending member near the end of attachment to the machine supporting the tongue from a higher part of the machine to take the weight of the tongue off of the steering means. 80 85

14. The combination, with a road making machine, of a tongue swingingly connected at its rear end to the machine, a pair of front wheels, means contacting the tongue to change the planes of the front wheels to steer the machine, and an elastic suspension from the tongue to a higher portion of the machine to take the weight of the tongue off of the steering means. 90

15. The combination, with a road making machine having a body member, of a front axle supporting the front end of the machine body; wheels supporting the axle at its ends said axle being a supporting member only and not for steering the machine body; spindles carrying the front wheels pivoted upon a vertical axis, means for rotating said wheels about said axis to steer the machine in the desired direction, a tongue, and a second steering means, said first steering means being operable without interfering with the second steering means or with the side swing of the tongue. 95 100 105

16. The combination, with a road making machine having a body member and a scraper blade, of a front axle supporting the front end of the machine body; wheels supporting the axle at its ends said axle being a supporting member only, not used for steering the machine body; a drawbar extending rearwardly of the front axle, for supporting the scraper blade; a short draw-bar extending through the front axle to the rear end of which the first draw-bar is attached, and a tongue flexibly attached to the front end of the short drawbar whereby the pull of the tongue is exerted directly through the short drawbar of the road making machine and not through a king pin. 110 115 120

17. The combination, with a road making machine having a body member and a scraper blade, of a front axle supporting the front end of the machine body; wheels supporting the axle at its ends, said front axle being a supporting member only and 125 130

not used for steering the machine body; a draw-bar extending rearwardly from the front axle, for supporting the scraper blade; a short draw-bar extending through the front axle to the rear end of which the first draw-bar is attached, a tongue flexibly attached to the front end of the short draw bar of said machine whereby the pull of the tongue is exerted directly through the short draw-bar without appreciably changing the point of such attachment with reference to the longitudinal center line of said road making machine.

18. The combination, with a road making machine having a body member and a scraper blade, of a front axle supporting the front end of the machine body; wheels supporting the axle at its ends, said front axle being a supporting member only and not used for steering the machine body; a drawbar extending rearwardly of the front axle for supporting the scraper blade; a short draw-bar extending through the front axle to the rear end of which the first draw-bar is attached; a tongue; and means for flexibly attaching the tongue to the front end of the short draw bar whereby the line of pull of said tongue may, or not, be parallel to the longitudinal center line of said machine body.

19. The combination, with a road making machine having a body member, of a front axle supporting the front end of the machine body; wheels supporting the axle at its ends, said front axle being a supporting member only and not for steering the machine body; spindles carrying the front wheels pivoted upon vertical axes; means for rotating said wheels about said axes to steer the machine body in the desired direction; a tongue; means for attaching it flexibly to the axle, means for operating the steering wheels by the tongue and means for operating them independently of the action of the tongue whereby the planes of the wheels may or may not be parallel to the longitudinal center line of the tongue.

20. The combination, with a road making machine comprising a machine body, of a front axle supporting the front end of the machine body; spindles carrying the front wheels pivoted upon vertical axes; means for swinging said wheels about said axes to steer the machine in the direction desired;

a tongue; means for flexibly attaching the tongue to the axle between the front wheels, means for operating said wheel-swinging machine-steering means by the swing of the tongue, and means for operating them independently of the swing of the tongue, said steering means being operable jointly or separately.

21. The combination, with a road making machine comprising a machine body, of a front axle supporting the front end of the machine body; spindles carrying the front wheels said spindles being pivoted on their vertical axes; means for swinging the wheels about said vertical axes to steer the machine; a steering tongue flexibly attached to the front axle; means connected with the steering tongue for operating said wheel-swinging machine-steering means and a second tongue for draft purposes secured to the first tongue.

22. The combination, with a road making machine comprising a machine body, of a front axle supporting the front end of the machine body; spindles carrying the front wheels said spindles being pivoted on upon their vertical axes; means for swinging the wheels about said vertical axes to steer the machine; a steering tongue flexibly attached to the front axle; means connected with the steering tongue for operating said wheel-swinging machine-steering means; a second tongue for draft purposes secured to the first tongue, and elastic suspension means connecting the tongues with a higher part of the machine body.

23. The combination, with a road making machine, of a steering tongue swingingly connected with the machine; a bar movable lengthwise of itself and laterally of the tongue across the tongue; a rack extending lengthwise of the bar; a front axle; spindles pivoted vertically to the axle ends and having rigid forward arms; road wheels on the spindles; link-bars connecting the ends of the movable bar with the respective spindle-arms; and means, comprising a pinion engaging the rack, for moving the bar to rock the spindles and thereby change the angles of the wheels to steer the machine.

In testimony whereof I affix my signature.

JOHN M. LARSH.

CERTIFICATE OF CORRECTION.

Patent No. 1,628,851.

Granted May 17, 1927, to

JOHN M. LARSH.

It is hereby certified that the above numbered patent was erroneously issued to the inventor, said Larsh, one-fourth to William Mode Taylor and one-fourth to Ulysses Grant Smith, as assignees, whereas said Letters Patent should have been issued to the inventor, said Larsh, one-half to William Mode Taylor, and one-fourth to Ulysses Grant Smith, both of Indianapolis, Indiana, as assignees; as shown by the records of assignments in this office; and that the said Letters Patent should be read with this correction therein that the same may conform to the record of the case in the Patent Office.

Signed and sealed this 7th day of June, A. D. 1927.

Seal.

M. J. Moore,
Acting Commissioner of Patents.
